REINFORCED SHIPPING CONTAINER AND
METHOD OF MAKING SAMECharles G. Jones and Walter F. Van De Venter,
Louisville, Ky., assignors to General Box Com-
pany, Chicago, Ill., a corporation of Delaware

Application April 30, 1942, Serial No. 441,058

3 Claims. (Cl. 217—69)

This invention relates to shipping containers and more particularly to such containers having metal reinforcements at the corner edges, and to the method of making the same.

In the type of shipping containers having their corner edges reinforced with angular metal strips having prongs punched out from their sides, such prongs being driven through the wooden or fibrous sides of the container and clinched over at their ends against the side face of the sides, end or bottom wall members of the container, it has, prior to our invention, been necessary to use ends such that either the ends or the sides might under heavy impact or pressure be forced inwardly thus damaging the container, and possibly the contents. This we have overcome by making the adjacent edges of the ends and sides of interlocking formation and bending that portion of the angle irons that will be secured to the ends, outwardly to such an angle that when the sides are being swung into assembled position with relation to the ends, the free ends of the prongs that are stamped out of the bent portion of the angle irons will clear the outer face of the adjacent end to permit the projections and recesses of the interlocking formation to snugly interfit, after which the said bent portion of the angle iron will be forced against the end to drive the prongs therethrough and the free ends of the prongs clinched into the inside face of the end. Indentations will be formed in the end to assist in the driving of the prongs through the end.

Among the objects of our invention are to overcome the objections and successfully accomplish the advantages and improvements referred to above.

A further object is to provide a container of greater strength, and one in which the sides and ends are firmly held against being pushed inwardly one with relation to the other.

A still further object is to provide a novel method of assembling the sides, ends and bottom of an angle iron reinforced container, in such manner that the sides may be swung against the ends with interlocking fit and without conflict between the prongs of the angle iron and the end, and then securing the angle iron to the end.

Another object is to provide a novel method in which the sides and bottom are secured together by pronged angle irons to form a mat, the ends secured to the angle irons, and the sides swung into interlocking engagement with the ends without the prongs that will be driven into the

ends conflicting with the ends during the swinging and interlocking movement.

A further object is to provide a novel container having interlocking sides and ends and angle iron reinforcement at the corner edges.

Other objects, advantages and capabilities will later more fully appear.

Our invention further resides in the combination, construction and arrangement of parts illustrated in the accompanying drawings, and while we have shown therein a preferred embodiment we wish it understood that the same is susceptible of modification and change without departing from the spirit of our invention.

15 In the drawings:

Fig. 1 is a perspective view of a container embodying our invention;

Fig. 2 is a fragmentary horizontal section on the line 2—2 of Fig. 1;

20 Fig. 3 is a fragmentary vertical section on the line 3—3 of Fig. 1;

Fig. 4 is a vertical section through one of the angle irons, on the line 4—4 of Fig. 5, but omitting the bottom wall member;

25 Fig. 5 is a perspective view of a mat comprising two side wall members and a bottom wall member with the angle irons secured thereto, and the mat in flat position;

Fig. 6 is a vertical section through one of the 30 angle irons through a plane passing through the line 6—6 of Fig. 5 but omitting the side wall member;

Fig. 7 is a side elevation of one of the end wall members;

35 Fig. 8 is a side elevation of one of the side wall members;

Fig. 9 is a perspective view of a mat in flat position similar to that shown in Fig. 5, but also showing the two end wall members in position 40 thereon, prior to swinging the side wall members upwardly to engage the end wall members.

Fig. 10 is a view similar to Fig. 9, but showing the side wall members partly swung towards closed position.

45 Fig. 11 is a fragmentary horizontal section through one end of the container prior to bending the outstanding flange of the angle iron against the end wall member to drive the prongs therethrough;

50 Fig. 12 is a fragmentary perspective view of the upper end portion of one corner of the container.

Referring more in detail to the drawings, the container of the present invention comprises side wall members 1 and 2, end wall members 3 and

4, bottom wall member 5, and metal angle irons 6 securely fastened along the corner edges of the container. As will be noted in Figs. 1 and 5 each of the angle irons comprises three sections 7, 8 and 9 integrally connected together, one section for each of the two sides and bottom and each of these sections having a flange to engage the outer face of the end wall member. As seen in Fig. 4 which is a cross section on the line 4—4 of Fig. 5 the section 8 of the angle iron, which is the section secured to the bottom wall member, comprises the legs or flanges 10 and 11 standing at right angles to each other to form a ninety degree angle, whereas the sections 7 and 9, shown in cross section in Fig. 6 comprise legs or flanges 12 and 13 which form an angle with relation to each other greater than ninety degrees. In the drawings this angle is shown as approximately one hundred and thirty-five degrees, although such angle may depart somewhat from one hundred and thirty-five degrees without departing from the spirit of our invention. The main requirement is that this angle be sufficiently larger than ninety degrees to permit the side walls to be swung upwardly into engagement with the end wall member without the prongs 14 striking against the edge of the end wall member as will later be more fully explained.

The angle irons 6, as stated, comprise the sections 7, 8 and 9 which are integrally connected together from end to end throughout the full length of the flanges connected to the two side wall members and the bottom wall member, this integral strip being shown in dotted lines in Figs. 5 and 9. Those flanges of the angle irons, which are secured to the end wall members, however, are formed with V-shaped notches 15 and 16, the apex of which falls on the bending line about which the side wall members are swung upwardly with relation to the bottom wall member as will be understood in Fig. 10. The angularity of these V-shaped notches 15 and 16 is such that when the side wall members are brought into final interlocking position with relation to the end wall members the edges forming the sides of the notch will substantially touch as shown at 17 in Fig. 1.

As seen in Figs. 4 and 5 the middle flange which connects with the end wall member is indicated at 11 and as seen in Figs. 5 and 6 each of the other two flanges that connect with the end wall member is indicated at 13. As the angle irons at both ends of the container are alike except for being reversed in position, only one of them need be described in detail. Also as seen in Figs. 4 and 5 the upstanding flange 11 stands at right angles with relation to the complementary flange 10 of the angle iron, while as seen in Figs. 5 and 6 the upstanding flanges 13 form approximately an angle of one hundred and thirty degrees with relation to the complementary flanges 12, or, as explained, such other obtuse angle as will permit the ends of the prongs 14 to move by or over the outer face of the end wall member as they are swung into assembled position.

Referring now to Fig. 7 it will be seen that the end wall members (they are both alike in construction) are provided along both of their vertical edges with a plurality of "tenon" projections provided by a series of projections 18 and recesses 19, while as shown in Fig. 8 the two vertical ends of the side wall members (they are both alike in construction) are provided with complementary tenon projections provided by projections 20 and recesses 21. When the wall members of the container are in final assembled posi-

tion the complementary tenon projections of the end wall members and the side wall members will be brought into interlocking engagement. See Figure 10.

5 The end wall members, as seen in Fig. 7, are each formed near their bottom edges with spaced apart indentations or holes 22 of a shape and so spaced as to receive the inwardly projecting prongs 23 of the flange 11 by positioning the end wall member in proper position thereover and tapping the same together with a hammer to bring the end wall members into the respective positions shown in Fig. 9. The free ends of these prongs will at the proper time be clinched over against and into the inner face of the end wall member with a suitable machine. Also the end wall members will preferably have formed along their vertical edge portions at suitably located positions indentations or holes 24 to assist the prongs 14 to enter the wood of the end wall members without being distorted when these prongs are driven into final position. As will be understood the prongs 25 will be driven through the side wall members and clinched on and into the inner faces thereof with a suitable machine. As will be also understood the prongs 26 will be driven through the bottom wall member and clinched on and into the inner face thereof with a suitable machine. Also the free ends of the flanges 12 and 13 will, by means of a suitable machine, be bent over the upper edges of the corners of the side wall members and the end wall members and clinched against and into the inner faces thereof as shown in Fig. 12.

In Fig. 2 the flange 13 is shown after it has been forced against the outer face of the end wall member and after the prongs 14 have been driven therethrough and clinched.

In assembling the parts of our improved container, a pair of the angle irons facing each other are placed in properly spaced apart position with holes over positioning pins or by means of any other suitable positioning means, and side wall members 1 and 2 and a bottom wall member placed in the angles of the angle irons as will be understood in Fig. 5, it being understood that will be done in a suitable machine which will also drive the prongs 25 through the side wall members, and the prongs 26 through the bottom wall member, these prongs also being clinched against and into the inner faces of these wall members. Also either previously to, or during this operation, the flanges 13 will each be bent outwardly to the obtuse angle previously described.

This results in the production of a mat such as shown in Fig. 5, it being understood that the free ends of the flanges 12 will be bent over the outer edges of the side wall members while the mat is being formed. The mat is then laid on a table (not shown) and the two end wall members placed in proper position thereon and driven at the bottom edge with a hammer to force the prongs 23 through the holes 22, after which operation the mat and end wall members will be as shown in Fig. 9, it being understood that the free ends of the prongs 23 will be clinched over against and into the inner face of the end wall member at any desired time thereafter with a suitable machine.

Next the side wall members will be swung upwardly and inwardly as indicated in Fig. 10. It is important to keep in mind that due to the arrangement of the respective complementary tenon projections 18 and 20 and the angle of the

flanges 13 with relation to the flanges 12 of the side wall sections of the angle irons, the complementary tenon projections referred to will move into interlocking position and simultaneously the prongs 14 will move over the outer faces of the end wall members without clashing therewith. After the side wall members are brought into firm interlocking relationship with the end wall members the angularly outstanding flanges 13 by means of any suitable machine will be bent into facial contact with the outer face of the end wall member and the free ends of the prongs 14 clinched on the inside thereof.

The indentations or holes 24 in the outer faces of the end wall members will be in proper position to receive the prongs 14 as the angularly outwardly bent flanges 13 are being bent flat against the end wall member, thus eliminating any danger that said prongs might become damaged by bending during such operation.

It will thus be understood that we have provided a novel metal reinforced container in which the meeting edges of the end wall members and the side wall members are interlocked against any possible pushing inward, and the bringing of the interlocking tenon projections into interengagement as the side wall members are swung upwardly against the end wall members is made possible by having the side flanges that engage the end wall members bent outwardly at such an angle that the prongs will clear the end wall members as the side wall members are swung into final position. This insures the positioning of the tenon projection interlock underneath the angle irons having prongs in both flanges throughout. This double locking means, to-wit, the interlocking corners and the angle iron prongs, eliminates any possibility of one of the walls of the container being pushed inwardly without breaking the container.

Having now described our invention, we claim:

1. A mat for making metal reenforced containers of the type having side and end wall members in abutted relation with each other, so as to prevent them from being pushed inwardly under heavy compact, said mat comprising a bottom wall member and two side wall members with one side wall member on each side of the bottom wall member, all of said wall members being laid out flat, an angle iron secured to each end of each of said wall members, said angle irons each having two flanges provided with prongs, the flanges at each end of the bottom wall members standing at 90 degrees with relation to each other, one of the last mentioned flanges being positioned to receive an end wall member, and the flanges at each end of each of the side wall members standing at an obtuse angle with relation to each other at such degree that when the side wall members and angle irons are swung inwardly with respect to interposed end wall members, so as to position the container sides against the end wall members, the obtuse angled prongs will clear the end wall members and allow of interengagement of the end wall members and the side wall members.

2. The method of making metal reenforced containers which consists in forming a mat containing a bottom wall member and two side wall members, with one side wall member on each side of the bottom wall member, and laid out flat,

each side wall member having tenon projections on the respective ends thereof, securing an angle iron to each of the respective ends of said side wall and bottom wall members, each angle iron having integral prongs in each of its flanges, and an upstanding flange at each end of each of the side wall members arranged at an obtuse angle with relation to its complementary flange, securing one edge of an end wall member to the upstanding flange at each end of the bottom wall member while the side and bottom wall members are in their flat position, each of the end wall members having tenon projections along each of its vertical side edges complementary to and engageable with the tenon projections of the side wall members, swinging the respective side wall members inwardly, so as to bring their tenon projections into interlocking engagement with the tenon projections of the end wall members, and also moving the upstanding obtusely angled flanges of the angle irons over the outer surfaces of the respective end wall members during said inward movement of the side wall members, so that said obtuse angled prongs clear the outer faces of the respective end wall members, and then bending said obtuse angled flanges against the respective end wall members and driving their prongs into the latter so as to form a container with abutted side and end wall members positioned to prevent inward movement of either of them, said container having metal reenforced corners.

3. The method of making metal reenforced containers which consists in forming a mat containing a bottom wall member and two side wall members, with one side wall member on each side of the bottom wall member and laid out flat, each side wall member having tenon projections on each end thereof, securing an angle iron to each of the respective ends of said side and bottom wall members, each angle iron having integral prongs in each of its flanges, and an upstanding flange at each end of each of the side wall members, each of said upturned flanges on the side wall members being bent to an obtuse angle with relation to its complementary flange, securing one edge of an end wall member to the upstanding flange at each end of the bottom wall member, while the side and bottom wall members are in their flat position, each of the end wall members having tenon projections along each of its vertical side edges complementary to and engageable with the tenon projections of the side wall members, simultaneously swinging the side wall members inwardly so as to bring their tenon projections into interlocking engagement with the tenon projections of the end wall members, and moving the upstanding obtusely angled flanges of the angle irons over the outer surfaces of the respective end wall members during said inward movement of the side walls, so that said obtuse angled prongs clear the outer faces of the respective end wall members, and then bending said obtuse angled flanges against the respective end wall members and driving their prongs into the latter, whereby to form a container with abutting side and end wall members positioned to prevent inward movement of either of them, said container having metal-reinforced end edge corners.

CHARLES G. JONES.
WALTER F. VAN DE VENTER.
